(57) **CLAIM**

The ornamental design for a cosmetic container, as shown and described.

DESCRIPTION

FIG. 1 is a perspective view of a cosmetic container showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a view showing the profile of the design along line 8-8 of FIG. 6.

The interior structure shown in broken lines are for illustrative purposes only; and form no part of the claimed design.

1 Claim, 8 Drawing Sheets
